W. P. MASON

STENCIL HAND STAMP

Filed April 30, 1923

UNITED STATES PATENT OFFICE.

WILLIAM PORTER MASON, OF NORFOLK, VIRGINIA.

STENCIL HAND STAMP.

Application filed April 30, 1923. Serial No. 635,636.

To all whom it may concern:

Be it known that I, WILLIAM P. MASON, a citizen of the United States, residing at Norfolk, in the county of Norfolk and State 5 of Virginia, have invented new and useful Improvements in Stencil Hand Stamps, of which the following is a specification.

This invention relates to a stencil hand stamp by means of which an impression 10 is formed upon a surface through a stencil held in contact therewith.

The general object of the invention is to provide a unitary device, simple in its construction and operation, by means of 15 which the stencil and stamping element may be held and guided so that the characteristic design or signature, or other mark, formed in the stencil, may be impressed on a surface in the same manner as an ordinary 20 hand stamp is used.

Other objects of the invention include novel means for removably supporting the stencil as well as a stamping element of 25 novel construction, and improved means for positioning the stamping element and for supplying ink thereto.

The nature of the invention will be best understood from the following detailed description taken in connection with the accompanying drawing, which illustrates the 30 preferred form of the invention.

In the drawing:—

Fig. 1 is a front elevation of the invention with parts shown in section.

Fig. 2 is a rear elevation thereof.

Fig. 3 is a vertical longitudinal section.

Fig. 4 is a sectional view on the line 4—4 of Fig. 2, with parts broken away.

Fig. 5 is a view similar to Fig. 3, but 40 showing the stamping element and plunger depressed.

Fig. 6 is a perspective view of the stencil and guide frame for holding the same.

The device comprising my invention 45 includes a U-shaped frame 1 having depending arms 2 and 3, at the lower ends of which is removably supported a guide frame 4, the latter having at its ends upturned flanges 5 which may be attached to the 50 arms 2 and 3 by screws 6 or the like.

The frame 4 is provided with a central rectangular opening on each side of which are formed longitudinal guides 7 in which the stencil frame 8 may be inserted. The 55 frame 8, as shown, carries a stencil 9 of paraffin paper or the like, on which the

signature or other design may be inscribed with a sharp pointed instrument. The specific nature of the stencil, however, is not an essential part of the invention and any 60 other stencil may be inserted in the same manner.

A guide collar 10 is secured centrally to the yoke 1 in any suitable manner. As shown, the collar 10 is formed with flanges 65 11 which are secured to the yoke by means of screws 12. A plunger, which carries the stamping element hereinafter described, is mounted within the frame 1 with its stem 13 mounted to reciprocate within the 70 collar 10. At the lower end of the stem 13, a reinforcing and supporting plate 14 is secured, to which a yoke 15 is attached by screws 16 or the like. The arms of the yoke are guided in suitable guideways 17 75 formed on the inner faces of the frame arms 2 and 3, and rotatably support the trunnions 18 of a stamping element 19. This stamping element is substantially cylindrical but provided with a plurality of 80 symmetrically-arranged flat faces 20 each of which is formed of a rubber pad and which are adapted to carry sufficient ink to form the desired impression when brought into contact with the stencil 9.

When the plunger stem 13 is depressed, the stamping element is brought into co-operative relation to the stencil and the several faces 20 are successively presented thereto. The means by which the step by 90 step rotation of the stamping element is effected, includes a ratchet wheel 21 secured to one of the trunnions 18 and provided with as many notches 22 as there are faces 20. A spring-actuating element 23 is supported 95 by a reinforcing plate 24 secured to the underside of the frame member 1. Each time the plunger rises, the lower end of the spring element 23 engages one of the notches 22, causing the partial rotation of the stamping element 19, while upon the downward movement of the plunger, the end of the spring element 23 rides freely over the surface of the wheel 21. A second spring-actuating element 25 is suitably secured to the yoke 15, as indicated at 26 in Fig. 3, and cooperates successively with the plurality of flat faces 27 formed on one of the trunnions 18 to position the cylinder 19, so that one of the faces 20 will always 105 be presented in parallel relation to the stencil 9.

The inking device comprises a roller 28 of porous material permeated with ink and resiliently supported by the spring arms 29 from the yoke 15. The spring arms 29 are so tensioned that the roller is always in contact with the surface of the cylinder 19, and as the plunger is reciprocated and the cylinder is rotated step by step, the ink is successively applied in turn to the several faces 20 of the cylinder, and these faces are subsequently brought in turn into operative relation to the stencil.

The stem 13 is provided at its upper end with a suitable knob or handle 30 having an internally-threaded socket 31 which is secured to the upper end of the stem and held in adjustable relation thereto by means of a lock nut 32. The stem 13 is hollow and a coil spring 33 is seated therein between the bottom of the socket 31 and an abutment 34, and is so tensioned as to restore the stamp element and plunger to its normal or uppermost position after each depression thereof. The abutment 34 is secured to the inner wall of the collar 10 and projects into the stem 13 through a slot 35 which extends longitudinally of the stem 13 for a sufficient distance to permit the reciprocation of the plunger.

From the foregoing description, it will be understood that after the stencil 9 has been inserted within the guideways 7, successive impressions may be made through the stencil by the stamping element 19 merely by the depression of the plunger by means of the handle 30. Each time the plunger is depressed, one of the faces 20 will be presented in parallel relation to the stencil, the proper positioning of the cylinder 19 being effected by the spring member 25 pressing against one of the flat faces 27. Upon release of the plunger handle, the spring 33 restores the plunger while the spring element 23 engages one of the notches 22 to cause the cylinder to be rotated to bring the next one of the flat faces 20 into stamping position.

The stencil frame 8 may be readily removed and a new stencil inserted whenever desired. By removing the screws 6 and the handle 30, the entire mechanism may be disassembled.

It will be seen, from the foregoing description, that I have provided a simple unitary device, all parts of which are successively operated merely by the depression of the plunger by means of the handle 30. The invention is particularly adapted for the use of stencils having characteristic features such for instance as a person's signature, which may be easily inscribed thereon, and the stencil afterwards inserted in the guideways 7 for use in the manner above described.

While I have shown and described the

specific details of one construction by means of which the invention may be carried out, it is to be understood that this is merely illustrative, and that various modifications may be made therein as long as such modifications mark no material departure from the salient features of the invention, as set forth in the following claims.

What is claimed is:

1. In a stencil hand stamp, the combination with a substantially U-shaped frame, a guide frame mounted at and connecting the lower ends of said U-shaped frame, guiding means provided on said guide frame, a stencil frame detachably mounted in said guiding means and carrying a stencil; a plunger; a spring for the plunger, and stamping means mounted within the U-shaped frame above the stencil and adapted to be actuated by the movement of the plunger to contact with the stencil and produce an impression.

2. In a stencil hand stamp, the combination of a frame, means for securing a stencil to the frame in contact with the surface on which the frame rests, a plunger reciprocable within the frame, a stamping element, and means operable upon reciprocation of the plunger, first to supply ink to the stamping element and then to cause the latter to print through a stencil secured in the frame.

3. In a stencil hand stamp, the combination of a frame, a stencil secured in the frame adapted to contact with the surface on which the frame rests, a plunger mounted to reciprocate within the frame, a plurality of stamping elements, and means operable upon reciprocation of the plunger to supply ink successively to the stamping elements and afterwards to cause each stamping element in turn to print through the stencil while ink is supplied to a succeeding stamping element.

4. In a stencil hand stamp, the combination of a frame, means for securing a stencil to the frame adapted to contact with the surface on which the frame rests, a plunger mounted to reciprocate within the frame and having a yoke within which a cylinder is rotatably mounted, said cylinder having a plurality of flat faces, an inking roller yieldably held in contact with the cylinder, means for rotating the cylinder to bring the flat faces successively into wiping contact with the roller and to subsequently bring said faces into stamping relation to the stencil.

5. In a stencil hand stamp, the combination of a U-shaped frame, a stencil frame mounted at the free ends of the U-shaped frame and provided with a stencil, a spring held plunger operating in the U-shaped frame and provided with a rotatable cylinder having a series of flat faces, an inking

- roller adapted to engage the faces of the cylinder, and means for rotating the cylinder step by step upon actuation of the plunger to bring the faces into contact with the inking roller successively and to subsequently bring said faces into contact with the stencil.
6. In a stencil hand stamp, the combination of a U-shaped frame, a stencil frame removably secured to the free ends thereof, a yoke having a stem reciprocably mounted in the frame, a stamping element carried by the yoke in operative relation to the stencil frame, a handle removably secured to the projecting end of said stem, said yoke, stem and stamping element being freely removable from the frame when the stencil guide and handle are removed.
7. In a stencil hand stamp, the combination of a substantially U-shaped frame, a guide frame mounted at and connecting the free lower ends of said U-shaped frame, said guide frame having a central opening with guides at each side, a stencil frame mounted in said guides and carrying a stencil, a plunger operating in said U-shaped frame, a spring for the plunger, a rotatable stamping cylinder for the cylinder carried by the plunger, means for inking the cylinder, and means whereby said cylinder is carried into contact with the stencil to make an impression through the stencil.
8. In a hand stamp, the combination of a frame, a plunger mounted to reciprocate therein, a stamping cylinder rotatably carried by the plunger and having a plurality of flat faces, a ratchet wheel carried by the cylinder, a resilient member secured to the frame and engageable with the ratchet wheel to cause a partial rotation of the cylinder upon movement of the plunger in one direction, means to gage the partial rotation of the cylinder and to cause it to stop with one of the flat faces always in the proper position for stamping, and an inking roller held in wiping contact with the cylinder.
9. In a stencil hand stamp, the combination of a U-shaped frame, a stencil frame mounted at and connecting the free ends of the U-shaped frame, and provided with a stencil, a plunger operating in the U-shaped frame, a spring for the plunger, a rotatable stamping cylinder for the stencil carried by the plunger, an inking roller for inking the cylinder, and means for holding the roller in contact with the cylinder and for causing the rotation of the roller by the rotary movement of the cylinder.

In testimony, that I claim the foregoing as my own, I have hereto affixed my signature.

WILLIAM PORTER MASON.
